US00D824496S

(12) **United States Design Patent** (10) **Patent No.:** **US D824,496 S**
(45) **Date of Patent:** **** Jul. 31, 2018**

(54) **URINAL SCREEN**

(71) Applicant: **GPCP IP HOLDINGS LLC**, Atlanta, GA (US)

(72) Inventors: **Daniel M. D'Amico**, South Salem, NY (US); **Eric P. Peterson**, Mount Horeb, WI (US); **David A. Hoadley**, Hortonville, WI (US); **Jacob Edward Malesky**, Menasha, WI (US)

(73) Assignee: **GPCP IP HOLDINGS LLC**, Atlanta, GA (US)

(**) Term: **15 Years**

(21) Appl. No.: **29/626,119**

(22) Filed: **Nov. 15, 2017**

Related U.S. Application Data

(62) Division of application No. 29/578,140, filed on Sep. 19, 2016, now Pat. No. Des. 806,837.

(51) **LOC (11) Cl.** **23-01**

(57) **CLAIM**

We claim the ornamental design for a urinal screen, as shown and described.

DESCRIPTION

FIG. 1 is a perspective view of a urinal screen showing our new design;

FIG. 2 is a front elevation view thereof, the rear elevation view being a mirror image thereof;

FIG. 3 is a right side elevation view thereof, the left side elevation view being a mirror image thereof;

FIG. 4 is a top plan view thereof;

FIG. 5 is a bottom plan view thereof;

FIG. 6 is a bottom perspective view thereof;

FIG. 7 is an enlarged top plan view of a partial portion of FIG. 4; and,

FIG. 8 is an enlarged perspective view of a partial portion of FIG. 1.

1 Claim, 7 Drawing Sheets
